CLAIM

The ornamental design for a microphone, as shown and described.

DESCRIPTION

FIG. 1 is a front, top, and left-side perspective view of a microphone showing the new design.

FIG. 2 is a front elevation view thereof.

FIG. 3 is a rear elevation view thereof.

FIG. 4 is a left-side elevation view thereof.

FIG. 5 is a right-side elevation view thereof.

FIG. 6 is a top plan view thereof.

FIG. 7 is a bottom plan view thereof; and,

FIG. 8 is a rear, bottom, and right-side perspective view thereof.

The broken lines shown in the drawings are for the purpose of illustrating portions of the depicted article and form no part of the claimed design.

1 Claim, 8 Drawing Sheets
